UNITED STATES PATENT OFFICE.

JOHN C. HASKETT AND CHARLES A. STUBBS, OF SPICELAND, INDIANA.

INTAKE-MANIFOLD MIXING DEVICE.

1,410,915.

Specification of Letters Patent. Patented Mar. 28, 1922.

Application filed February 24, 1921. Serial No. 447,459.

To all whom it may concern:

Be it known that we, JOHN C. HASKETT and CHARLES A. STUBBS, citizens of the United States, residing at Spiceland, in the county 5 of Henry, State of Indiana, have invented a new and useful Intake-Manifold Mixing Device; and we do hereby declare the following to be a full, clear, and exact description of the invention, such as will enable 10 others skilled in the art to which it appertains to make and use the same.

The invention relates to intake manifold mixing devices, and has for its object to provide a device of this character comprising substantially a flat member adapted to be disposed between the flanges of the intake manifold and the carburetor, said member being provided with an arched central portion arching the aperture in said flat member 20 which registers with the passage in the intake manifold, said arching portion forming means for preventing displacement of the device when the intake manifold or carburetor is removed, said arching device having pivotally mounted thereon and to rotate in a horizontal plane a mixing wheel, which wheel is rotated on the intake strokes of the pistons of the engine and forms means whereby the gases will be thoroughly mixed 25 and volatilized.

With the above and other objects in view the invention resides in the combination and arrangement of parts as hereinafter set forth, shown in the drawings, described and 35 claimed, it being understood that changes in the precise embodiment of the invention may be made within the scope of what is claimed without departing from the spirit of the invention.

40 In the drawings:—

Figure 1 is a side elevation of a conventional form of carburetor and a portion of an intake manifold showing the device applied between the flanges thereof.

45 Figure 2 is a top plan view of the device. Figure 3 is a vertical sectional view taken on line 3—3 of Figure 2.

Referring to the drawings, the numeral 1 designates a conventional form of carburetor 50 and 2 the flange thereof, which flange is connected to the flange 3 of the intake manifold 4 by means of bolts 5. It has been found that gases which are sucked through the manifold 4 are not sufficiently volatilized 55 and mixed and to accomplish this result a substantially flat member 6 is disposed be-

tween the flanges 2 and 3 of the carburetor and the intake manifold, said flat member being provided with apertures 7 through which the securing bolts 5 pass, thereby providing means whereby the same bolts 5 which hold the flanges 2 and 3 together also hold the member 6 in place. The member 6 is provided with a centrally disposed opening 8, which opening registers with the opening in the manifold 4 and through said opening gases on their way from the carburetor to the intake manifold pass. The member 6 is provided with a struck up portion 9 which arches the opening 8 and is provided with a centrally disposed pin 10 which is axially disposed in the opening 8 and on which pin a rotatable bladed member 11 is disposed, and which bladed member on the impulse or suction strokes of the pistons is rapidly rotated by the gases sucked past the same thereby causing the rapidly rotating blades to break up particles of the gases and thoroughly mix the gases in such a manner that the charge is volatilized and consequently the efficiency of the fuel increases.

From the above it will be seen that a gas mixer for internal combustion engines is provided, which mixer may be easily and quickly disposed between the flanges of the carburetor and the intake manifold, and one wherein the construction is simple and the parts reduced to a minimum.

The invention having been set forth what is claimed as new and useful is:—

1. The combination with a carburetor and an intake manifold having flange connections, said flange connections being held together by bolts, of a mixing device interposed between said flanges, said device comprising an apertured plate having a centrally disposed opening registering with the opening in the intake manifold, a struck out member arching the centrally disposed opening and a bladed wheel pivotally mounted on the struck out portion and axially disposed in relation to the centrally disposed opening and disposed in the same plane as the apertured plate.

2. The combination with a carburetor and an intake manifold having flanges connected together by bolts, of a gas mixer for mixing the gases as they pass from the carburetor to the intake manifold, said gas mixer comprising a plate interposed between the flanges of the carburetor and the intake manifold and through which plate the flange securing

bolts pass, said plate being provided with a centrally disposed aperture through which the gases pass, an integral struck out arching member arching the opening in the plate and 5 provided with a portion parallel with the plate, an axially disposed wheel pivotally mounted on a pin carried by the parallel portion of the arched member and forming means whereby the gases will be thoroughly 10 mixed as they pass from carbureter to the

intake manifold, said wheel being in the same plane as the plate.

In testimony whereof we have signed our names to this specification in the presence of two subscribing witnesses.

JOHN C. HASKETT.

CHARLES A. STUBBS.
